(Cl. 250—20)

This invention relates to super-heterodyne receivers wherein the oscillator and the aerial are coupled to the mixing tube in such a way that the oscillator-tube will not radiate over the aerial. By mixing tube we refer to a tube in which the super-position and rectifying of two oscillations takes place.

The invention refers to a device for super-position of two ultra-high frequency electro-magnetic systems of oscillations respectively for decoupling of two such systems of oscillations, especially for application to super-heterodyne receiving apparatus. In such case there can be used a Lecher-system to which the one oscillation is led. The other conductor of this Lecher-system branches in two conductors which form a second Lecher-system to which the second oscillation is led. The arrangement of these two Lecher-systems is made in such manner that the two conductors of the branching system oscillate in push-pull and both together work with respect to the other conductor of the first Lecher-system in the same rhythm.

For a fuller description of my invention reference is made to the accompanying drawings.

Figure 1 shows a circuit which embodies the invention as applied to the reception of radio frequencies generally.

Figure 2 shows an arrangement which corresponds to the general scheme of Fig. 1 and which at the same time shows the application of the invention to the special case of ultra-short waves. In this case the Lecher-systems are shown as comprising pipe-conductors.

Figure 3 shows the coupling of the two Lecher-systems effected by the insertion of a current-loop of one Lecher system into the magnetic field of the other Lecher-system.

Figure 4 shows the coupling being made by means of a slot in the outer conductor of the one Lecher-system.

Figs. 3a and 4a show cross sectional views of the arrangement of the Lecher-system taken on the lines 3a—3a and 4a—4a, respectively, of Figs. 3 and 4.

In Fig. 1 there is shown schematically a bridge-network. A two wire system 5, 5' carrying signal frequency from the aerial A is connected to a resonant circuit 6 consisting of capacity 6a and inductance 6b in parallel connection. From the resonant circuit 6 the conductors lead to the two blocking condensers 7 and 7' and from there to the mixing tube as for example to the anodes 8 and 8' of a duo-diode 23. To the center tap of the inductance 6b of the resonant circuit 6 on

one hand and to the cathode 9 of the duo-diode on the other hand there are connected the two conductors 10, 10' of a Lecher-system which lead from an oscillator-tube. Furthermore the primary windings 11, 11' of a push-pull transformer for the intermediate frequency are connected to the anodes 8 and 8'. The two windings 11 and 11' are counterwound. In order to prevent the high frequency from flowing to the intermediate frequency transformer the two resonant circuits 12 and 12' are inserted in the connection wires between the anodes 8 and 8' and the windings 11 and 11'. The thick lines in Fig. 1 indicate the conductors of the high frequency circuit while the thin lines show the conductors of the intermediate frequency circuit.

The circuit shown in Fig. 1 acts as follows:

The energy lines 10 and 10' lead from an oscillator which sets up high frequency oscillations and are connected to the bridge device. Both anodes 8 and 8' of the duo-diode oscillate in the same rhythm with respect to the cathode 9. The high frequency current from the line 10 flows through both halves of the inductance of the resonant circuit 6, through the blocking condensers 7, 7', through the anodes 8 and 8', through the cathode 9 of the duo-diode and from there back to the oscillator through the line 10'. (The inductance of the parallel resonance circuit 6 can be compensated by a capacity in the lead.) This high frequency current produces a direct current flow from the cathode 9 of the duo-diode to the centre of the primary windings 11, 11' of the intermediate frequency transformer. This direct current will not produce any potential difference at the secondary windings of the intermediate transformer, for both the halves of the windings 11 and 11' are counter-wound. Since equal currents flow from the centre to the ends of the primary windings 11 and 11' there will be no change of potential in the secondary windings. If on the contrary there exists a high frequency voltage in the energy line 5, 5' leading from the aerial the anodes 8 and 8' of the duo-diode will oscillate in push-pull. The currents which flow in the primary windings 11 and 11' of the transformer have the same direction. Currents of this kind will not compensate each other with respect to the secondary windings but produce a direct current voltage at the terminals of the secondary windings. The high frequency current coming from the aerial flows through wire 5 and blocking condenser 7 to anode 8 of the duo-diode and from there to cathode 9, winding 11', and anode 8', and from there to blocking condenser 7' through

the wire 5' back to the aerial, or through wire 5', blocking condenser 7', anode 8', cathode 9, winding 11, blocking condenser 7, and wire 5 of the aerial circuit.

In Figure 2 an arrangement corresponding to the scheme of Fig. 1 is shown which is suitable for use in receiving ultra-short waves especially waves of a wave length less than 1 meter. The first Lecher-system comprises the conductors 1 and 2 which lead from the oscillator-tube. The conductor 1 branches into two conductors 3 and 4 at the point 13. These new conductors form a second Lecher-system consisting of two wires having a length of $\lambda/2$ or a multiple thereof. (λ =wave length.) The system 3 and 4 is short circuited by a reflecting plate 14 constituting a bridging device. The conductors 3 and 4 form a resonator between 13 and 14 which, when excited, oscillates in push-pull. On the other hand, the conductor 2 may be connected to the plate 14 thereby establishing a potential node at this point for the Lecher-system 1, 2. Thus it is seen that a high frequency oscillation is set up over the system 1, 2 which produces a rhythmical oscillation of the conductors 3 and 4 together with respect to the conductor 2. The push-pull oscillations can be set up by an opening 15 in the reflecting plate 14 with the aid of current coupling. The duo-diode is then connected near to a potential loop between the conductors 3 and 4, i. e. in a distance of $\lambda/4$ from the plate 14 in such manner that the anodes 8 and 8' and the blocking capacities 7, 7' are connected with conductors 3 and 4 respectively while the cathode 9 is directly connected with conductor 2. The duo-diode tube presents an impedance which must be compensated, hence it will be found necessary to make the length of the conductors 3 and 4 not exactly $\lambda/2$ but of a length equivalent to $\lambda/2$ in such manner that the Lecher-system may be tuned to the desired wave length.

In Figure 3 the arrangement according to Fig. 2 is repeated except that in this case a concentrically formed Lecher-system is employed. The two conductors 3 and 4 are connected to the branching point 13 in form of a wire bridle in the same manner as shown in Figure 2. In order to illustrate the construction of this device more clearly a cross-section taken on the line 3a—3a of Fig. 3 looking in the direction of the arrows is shown in Fig. 3a. The wires 3 and 4 are short circuited with the outer conductor 2 at 16 through capacity 17, so that the rhythmical oscillation lead from 1, 2 has a potential node at 16. A second concentric Lecher-system 14, 18 is arranged so that its outer conductor 14 serves as a reflector plate for the conductors 3 and 4. The conductor 14 has an opening through which the conductors 3 and 4 project in form of a current loop 19 into the magnetic field of the Lecher-system 14, 18. In order to obtain a perfect symmetric coupling to the system 14, 18 in regard to the conductors 3 and 4 it is advantageous to provide the loop 19 in a potential node of the Lecher-system 14, 18. The center of the loop 19 has thus a distance of $\lambda/2$ or a multiple thereof of the short-circuited end 20 of the system 14, 18. From this follows that by such arrangement the aerial oscillation introduced at 21 causes no rhythmical oscillation at 22 and vice versa the oscillation of the oscillator-tube introduced at 22 causes no push-pull oscillation at 21. This is a consequence of the symmetry of the arrangement. If when the device is placed under actual operating conditions it is found that symmetry

is not preserved it can be restored with the aid of small trimming capacities connected between the conductors 3 and 4 on the one hand and the outer conductor 2 on the other hand.

- 5 Near to a potential loop of the system 3, 4 the anodes 8, 8' of the duo-diode 23 are coupled to the conductors 3 and 4 through the blocking condensers 7 and 7' and the cathode 9 is connected to the jacket 2. The direct current can be drawn 10 from the wires 24 which are arranged to be free of inductance and parallel to the conductors 3 and 4. They can run in the inner space of the hollow conductor 1 to the intermediate transformer. 15 Figure 4 shows another embodiment of the invention. Instead of a current loop 19 projecting into the magnetic field of the Lecher-system 14, 18 as shown in Figure 3 there is provided a slot 25 in the outer conductor 14 symmetrically 20 with respect to the conductors 3 and 4, thereby effecting a coupling between the Lecher-systems 14, 18 and 3, 4. The blocking condensers 26 and 26' may comprise concentric pipes insulated from the conductors 3 and 4. The anodes of the duo-diode 23 are connected directly to these condensers. The pipes 26 and 26' also act as a second Lecher-system for they carry the push-pull oscillation as well as that of the conductors 3 and 4. The arrangement shown in Figure 4a is a cross- 25 sectional view along the line 4a—4a looking in the direction of the arrows. The wires 24 for the direct current are connected in a potential node to the blocking condensers 26 and 26' and are extended through and insulated from contact 30 with the hollow conductor 1 and are connected to the intermediate frequency transformer by the wires 24. 35

It is advantageous as shown in all figures to provide the aerial-oscillation as push-pull oscillation and the oscillator oscillation as rhythmical oscillation for the push-pull oscillation needs no high frequency energy in the cathode conductors. These cathode conductors are advantageously made from thin wires in order to prevent 40 heat losses which cause a strong damping effect on the weak aerial oscillations. On the other hand since the oscillator possesses a correspondingly large amount of energy the damping will not affect it.

50 What we claim is:

1. A device for superposition of two ultra-high-frequency oscillations, comprising a Lecher-system to which one oscillation is led, one conductor of the said Lecher-system branching into two 55 conductors forming a second Lecher-system to which the other oscillation is led, a bridging device for said second Lecher-system said second Lecher-system oscillating with respect to the first Lecher-system in such manner that the two conductors of the branching system oscillate in push-pull with respect to said bridge device, and both together oscillate rhythmically with respect to the other conductor of the first Lecher-system. 60 2. A device for superposition of two ultra- 65 high-frequency oscillations, comprising a Lecher-system to which one oscillation is led, one conductor of the Lecher-system branching in two conductors forming a second Lecher-system to which the other oscillation is led, a bridging device for said second Lecher-system said second Lecher-system oscillating with respect to the first Lecher-system in such manner that the two conductors of the branching system oscillate in push-pull with respect to said bridge device, and both 70 together oscillate rhythmically with respect to 75

the other conductor of the first Lecher-system, said branching point being formed at a potential node for the push-pull oscillation.

3. A device for superposition of two ultra-high-frequency oscillations, comprising a Lecher-system to which one oscillation is led, one conductor of the Lecher-system branching in two conductors forming a second Lecher-system to which the other oscillation is led, a bridging device for said second Lecher-system, said second Lecher-system oscillating with respect to the first Lecher-system in such manner that the two conductors of the branching system oscillate in push-pull with respect to said bridge device, and both together oscillate rhythmically with respect to the other conductor of the first Lecher-system, both Lecher-systems being short circuited by said bridge at the point of a joint potential node, said point having a distance of $\lambda/2$ from the branching point.

4. A device for superposition of two ultra-high-frequency oscillations, comprising a Lecher-system to which one oscillation is led, one conductor of the Lecher-system branching in two conductors forming a second Lecher-system to which the other oscillation is led, a bridging device for said second Lecher-system said second Lecher-system oscillating in regard to the first Lecher-system in such manner that the two conductors of the branching system oscillate in push-pull with respect to said bridge device, and both together oscillate rhythmically with respect to the other conductor of the first Lecher-system, both Lecher-system being excited to push-pull oscillations by a slot formed in the short circuiting bridge and provided symmetrically to the two conductors of the second Lecher-system.

5. A device for superposition of two ultra-high-frequency oscillations, comprising a Lecher-system to which the oscillation is led, one conductor of the Lecher-system branching in two conductors forming a second Lecher-system to which the other oscillation is led, a bridge device for said second Lecher-system, said second Lecher-system oscillating with respect to the first Lecher-system in such manner that the two conductors of the branching system oscillate in push-pull with respect to the said bridge device, and both together oscillate rhythmically with respect to the other conductor of the first Lecher-system, both Lecher-systems being excited to push-pull oscillations by a gap in the short circuiting bridge, the two conductors of the second Lecher-system behind the bridge forming a current loop, coupling a high frequency magnetic field.

6. A device for superposition of two ultra-high-frequency oscillations, comprising a Lecher-system to which the oscillation is led, one conductor of the Lecher-system branching in two conductors forming a second Lecher-system to which the other oscillation is led, a bridge device for second Lecher-system, said second Lecher-system oscillating with respect to the first Lecher-system in such manner that the two conductors of the branching system oscillate in push-pull with respect to the said bridge device, and both together oscillate rhythmically with respect to the other conductor of the first Lecher-system, both Lecher-systems being concentrically formed and being short-circuited by a bridge at the point of a joint potential node said bridge being formed by the outer conductor of a

further concentric Lecher-system, coupling taking place in a potential node.

7. A device for superposition of two ultra-high-frequency oscillations, comprising a Lecher-system to which the oscillation is led, one conductor of the Lecher-system branching into two conductors forming a second Lecher-system to which the other oscillation is led, a bridge device for said second Lecher-system said second Lecher-system oscillating with respect to the first Lecher-system in such manner that the two conductors of the branching system oscillate in push-pull with respect to the bridge device, and both together oscillate rhythmically in regard to the other conductor of the first Lecher-system, a potential loop formed by said second Lecher-system an impedance connected between both conductors of the second Lecher-system, the center of said impedance being connected with the other conductor of the first Lecher-system.

8. A device for superposition of two ultra-high-frequency oscillations, comprising a Lecher-system to which the oscillation is led, one conductor of the Lecher-system branching into two conductors forming a second Lecher-system to which the other oscillation is led, a bridge device for said second Lecher-system said second Lecher-system oscillating with respect to the first Lecher-system in such manner that the two conductors of the branching system oscillate in push-pull with respect to said bridge device, and both together oscillate rhythmically with respect to the other conductor of the first Lecher-system, a potential loop formed by said second Lecher-system and an impedance comprising a duo-diode connected between the conductors of said second Lecher-system, the anodes of the duo-diode being connected through blocking condensers with the conductors of the second Lecher-system, the cathode being connected to the other conductor of the first Lecher-system.

9. A device for superposition of two ultra-high-frequency oscillations, comprising a Lecher-system to which the oscillation is led, one conductor of the Lecher-system branching into two conductors forming a second Lecher-system to which the other oscillation is led, a bridge device for said second Lecher-system said second Lecher-system oscillating with respect to the first Lecher-system in such manner that the two conductors of the branching system oscillate in push-pull with respect to the said bridge device, and both together oscillate rhythmically with respect to the other conductor of the first Lecher-system, said push-pull oscillations being excited by an aerial, said rhythmical oscillations being excited by an oscillator.

10. A device for superposition of two ultra-high-frequency oscillations, comprising a Lecher-system to which one oscillation is led, one conductor of the Lecher-system branching into two conductors forming a second Lecher-system to which the other oscillation is led, a bridge device for said second Lecher-system said second Lecher-system oscillating with respect to the first Lecher-system in such manner that the two conductors of the branching system oscillate in push-pull with respect to the bridge device, and both together oscillate rhythmically with respect to the other conductor of the first Lecher-system, near a potential loop formed by said second Lecher-system an impedance is connected between both conductors of the second Lecher-system, said impedance comprising a duo-diode, the

anodes being connected through blocking condensers with the conductors of the second Lecher-system, the cathode being connected to the other conductor of the first Lecher-system, said push-pull oscillations being excited by an aerial, said rhythmical oscillations being excited by an oscillator, the intermediate frequency being led free of inductance from the anodes of the duodiode to the branching point and from there along the inner conductor of the first Lecher-system to a push-pull transformer, the center of which is connected with the other conductor of the first Lecher-system.

11. A device for the superposition of two ultra-high frequency oscillations comprising a Lecher-system to which one oscillation is led, said Lecher-system being formed of an outer tubular conductor and an inner conductor, said inner

conductor spaced from said outer tubular conductor and concentric therewith branching into two conductors forming a second Lecher-system to which the other oscillation is led, a bridging device for said second Lecher-system, said second Lecher-system oscillating with respect to said first Lecher-system in such a manner that the two conductors of the branching system oscillate in push-pull with respect to the said bridging device and both together oscillate rhythmically with respect to the outer conductor of the said first Lecher system, said inner conductor branching at a potential node for the push-pull oscillations.
